UNITED STATES PATENT OFFICE.

HAROLD H. JONES, OF KALAMAZOO, MICHIGAN, ASSIGNOR TO KALAMAZOO VEGETABLE PARCHMENT COMPANY, OF KALAMAZOO, MICHIGAN.

PACKAGE FOR CIGARS, CANDY, AND THE LIKE.

Application filed March 7, 1927. Serial No. 173,564.

The main objects of this invention are:

First, to provide an improved package for cigars, candy and the like which effectively protects the article enclosed, permits the inspection thereof and affords ready accessibility.

Second, to provide an improved package for cigars and the like which permits the wrapping and sealing of the package with the 10 cigars enclosed therein in a wrapping machine without likelihood of injuring the contents.

Third, to provide an improved package of the class described by means of which the 15 contents are preserved with the moisture therein as for cigars, or with the moisture excluded as is desirable in certain confections.

Objects pertaining to details and economies of my invention will definitely appear 20 from the detailed description to follow. The invention is defined and pointed out in the claims.

A structure embodying the features of my invention is clearly illustrated in the accompanying drawing forming a part of this application, in which:

Fig. 1 is a perspective view of a cigar package embodying the features of my invention.

Fig. 2 is a cross section, a cigar being shown conventionally.

Fig. 3 is a perspective view of the open-sided box-like frame.

Fig. 4 is a perspective view with the package open for removal of its contents.

My improved package comprises a box-like frame consisting of opposed side walls 1 and 2 and opposed end walls 3 and 4. These are formed of a strip of paper of suitable width 40 scored to facilitate folding, the wall 4 having a flap 5 which is disposed within and glued to the wall 2. The wall 2 has an opening 6 extending from the end wall 3, this opening 6 weakening the wall sufficiently at 45 the corner 7 as to insure breaking or fracturing at that point when the opening 6 is engaged as by the thumb nail. Slits 8 are preferably provided to facilitate breaking at this point. However, sufficient stock is left 50 to prevent breaking of the frame in handling.

The wrapper 9 is wrapped around the frame after the contents, such as a cigar indicated at 10, are inserted, the ends of the wrapper being folded at 11 and sealed. The 55 wrapper is preferably formed of waxed

paper, that is, paper that has been treated with paraffin wax, which renders it transparent and also moisture resisting.

The overlapping flaps of the package are heated which causes the paraffin to melt sufficiently to seal the flaps. The contents are thus completely enclosed but may be inspected through the open panels of the frame, the wrapper constituting side panels for the frame.

When it is desired to open the package the wrapper may be readily fractured over the opening 6, the opening engaged with the thumb-nail, the frame fractured, and the wrapper torn open as indicated in Fig. 4. 70 The pull on the frame fractures it at its weakened point and the paper is torn along the side of the frame as it is lifted up as shown in Fig. 4.

My improved package is especially well 75 adapted for cigars as they are kept fresh and moist for a considerable period of time or protected from dust either in the pocket or on the counter. Further, the wrappers may be applied by wrapping and sealing machines 80 which is of very great advantage, and this is effected without injury to the contents.

I have illustrated and described my package as I have embodied it for cigars although it is well adapted for confectionery and other 85 articles where it is desired to protect the same and at the same time provide a package which may be readily opened.

Having thus described my invention what I claim as new and desire to secure by Letters 90 Patent is:

1. A package comprising an open sided frame member having an opening in one of its side walls extending from the adjacent end wall, and an enclosing wrapper of transparent material having sealed closing flaps disposed at the ends of the frame whereby the contents of the receptacle are completely closed in a sealed package and are visible through the open sides of the frame, said 100 wrapper overlying said opening in said frame, said opening facilitating the fracturing of the wrapper over said opening and permitting engagement of the end of the frame through said opening and the fracturing of 105 the frame at the corner adjacent said opening and the tearing of the wrapper along the edges of the frame as it is pulled apart exposing the contents of the package.

2. A package comprising an open sided 110

frame member having a fingernail opening adjacent one end thereof providing an engaging and a fracturing point, and an enclosing wrapper completely enclosing said frame and overlying said nail opening therein, said nail opening facilitating the fracturing of the wrapper over the opening and the engagement of the frame through the fractured

wrapper, and the fracturing thereof at a pre-determined point and the tearing of the 10 wrapper along the edges of the frame as it is pulled apart exposing the contents of the package.

In witness whereof I have hereunto set my hand.

HAROLD H. JONES.
